PROCESS FOR MANUFACTURING CLIPS

Filed May 14, 1928

UNITED STATES PATENT OFFICE.

CLIFFORD H. BALDWIN, OF LANSING, MICHIGAN.

PROCESS FOR MANUFACTURING CLIPS.

Application filed May 14, 1928. Serial No. 277,644.

My invention relates to a process for manufacturing the clip, or attaching piece, for brake rods for automobiles and similar parts and an object of my improvement is to cheapen the production and to improve the quality of such articles.

In the accompanying drawing:—

Figure 1 is a perspective view of a portion of a strip of metal from which the blanks 10 are cut, from which blanks the parts of the finished clips are to be made.

Figure 2 is a plan view of a portion of the strip of Figure 1, the lines on which the finished parts are to be formed being indicated 15 by broken lines.

Figure 3 is a perspective view of the blank as it is cut from the strip of Figure 1.

Figure 4 is a perspective view of one of the two entirely similar parts out of which 20 the clip is formed.

Figure 5 is an elevation showing the way the parts of the clip are placed together.

Figure 6 is a perspective view of a finished clip.

25 In the process of my invention I first form a strip 2 of metal, as shown in Figure 1, the side edges of which are parallel, which strip is flat for perhaps a third of its width inward from its edges, these flat portions being in the same plane and of the same thickness, as indicated at 2^b. The strip is then bent slantingly upward between the portions 2^b and continued in a flat portion 2^a, which is of a greater thickness than the portion 2^b and is 30 in a plane a short distance above the plane of the part 2^b.

I then cut the strip 2 on the lines a—a, parallel to each other and to the end of said strip and a distance apart equal to the width 40 of the clip to be made. This divides the strip 2 into a plurality of parts 3, such as shown in Figure 3, which form the blanks from which the parts of the finished clips are made.

The blank, as above described, is placed in 45 a die which forms it as indicated by broken lines in Figure 2, at the left of said figure, and divides it into equal portions by a transverse cut in the line b—b, and forms the head 2^a, with a central aperture 2^d therein and also 50 forms a longitudinal groove 2^c across the up-

per face of the part 2^a, as indicated by broken lines in Figure 2 and in full lines in one of the parts of said blank, as shown in Figure 4. The two parts formed from a single blank, as above described, are then placed together, 55 as illustrated in Figure 5, with the upper surfaces of the raised portions, as shown in Figures 1 and 3, bearing against each other. These surfaces are then united by welding, forming the finished article shown in Figure 60 6, which, however, may be further shaped, if required, by turning the united portions into a cylindrical form, as indicated by the broken lines 5 in Figure 6 and the aperture 4 may be bored therein to receive the brake 65 rod.

What I claim is:

1. In a process of forming articles of the kind described, providing a strip of metal with flat lateral portions in the same plane 70 and a raised intermediate portion, dividing said strip by transverse cuts into blanks of the required width, dividing said blanks into two like parts by a central transverse cut, placing the bentup surfaces of said parts into 75 engagement and welding them together.

2. In a process of forming articles of the kind described, providing a strip of metal with flat lateral portions in the same plane, a raised intermediate portion of greater thickness than said lateral portions, dividing said strip by transverse cuts into blanks of the required width, dividing said blanks into two like parts by a central transverse cut, placing the bentup surfaces of said parts into 80 engagement and welding them together.

3. In a process of forming articles of the kind described, providing a strip of metal with flat lateral portions in the same plane and a raised intermediate portion, dividing 90 each strip by transverse cuts into blanks of the required width, shaping said blanks in suitable die, dividing the same by a central transverse cut, placing the bent up surfaces of said parts into engagement and welding 95 them together.

In testimony whereof, I sign this specification.

CLIFFORD H. BALDWIN.
